United States Patent Office

Des. 233,770
Patented Nov. 26, 1974

233,770

ANIMAL TRAINING DEVICE

Melvin Phillip Clark, and Sandra Kay Clark, R.R. 3,
Box 5, Rema, Edwardsburg, Mich.

Filed Mar. 14, 1973, Ser. No. 341,163

Term of patent 3½ years

Int. Cl. D30—99

U.S. Cl. D30—42

FIG. 1 is a perspective view of an animal training device showing our new design;

FIG. 2 is a front elevational view;

FIG. 3 is a top plan view;

FIG. 4 is a bottom plan view; and

FIG. 5 is a right side elevational view.

We claim:

The ornamental design for an animal training device, substantially as shown and described.
